United States Patent Office

Des. 200,061

Patented Jan. 12, 1965

200,061

PLATE OR SIMILAR ARTICLE

Wataru Uda, 2181 Central Road, Apt. A, Fort Lee, N.J.

Filed Jan. 7, 1964, Ser. No. 78,105

Term of patent 3½ years

(Cl. D44—15)

The figure is a plan view of a plate or similar article showing my new design, a portion of the design being shown between dotted lines and a repeat portion being shown between dot-and-dash lines.

The plate is of a conventional configuration when viewed from the side and bottom thereof.

I claim:

The ornamental design for a plate or similar article, substantially as shown and described.
